United States Patent Office

Des. 196,839
Patented Nov. 12, 1963

196,839

COMBINED LOUDSPEAKER CABINET AND SUPPORT FRAME THEREFOR

Harold V. Dorgan, Chicago, Ill., assignor to J. H. Keeney & Co., Inc., Chicago, Ill., a corporation of Illinois

Filed May 18, 1962, Ser. No. 70,190

Term of patent 3½ years

(Cl. D26—14)

FIG. 1

FIG. 2

FIG. 3

FIG. 4

FIGURE 1 is a front perspective view of a combined loudspeaker cabinet and support frame therefor showing my new design;

FIG. 2 is a rear elevation of the device of FIG. 1;

FIG. 3 is a front perspective view of the device of FIG. 1 with a combined cigarette dispensing and record selecting machine being shown in broken lines for illustrative purposes only; and

FIG. 4 is a reduced side elevational view thereof.

I claim:

The ornamental design for a combined loudspeaker cabinet and support frame therefor, as shown and described.
